(57) **CLAIM**

The ornamental design for a strainer frame for supporting a straining material to strain paint, as shown and described.

DESCRIPTION

FIG. 1 is a bottom perspective view of a strainer frame for supporting a straining material to strain paint showing the new design;

FIG. 2 is a top perspective view thereof;

FIG. 3 is a top view;

FIG. 4 is a bottom view;

FIG. 5 is a right side view, the left side view being a mirror image thereof; and,

FIG. 6 is a front view, the rear view being a mirror image thereof.

The broken lines shown in the drawings are for the purpose of illustrating portions of the article and form no part of the claimed design.

1 Claim, 6 Drawing Sheets
